UNITED STATES PATENT OFFICE

ANDREW C. BOLTON, OF MIAMI, FLORIDA

KNIFE GAUGE

Application filed June 29, 1931. Serial No. 547,712.

This invention relates to new and useful improvements in cutting devices, and particularly to paring knives.

One object of the invention is to provide a gauge for attachment to the blade of a paring knife, of such construction that the same may be easily and quickly applied to the blade without the use of any tools, or any modifications to the blade.

10 Another object is to provide a gauge device of this character which, after having been applied to the blade of a knife, may be easily and conveniently manipulated, whereby to adapt the knife for cutting slices 15 of different thicknesses.

Other objects and advantages will be apparent from the following description, when taken in connection with the accompanying drawing.

20 In the drawing:

Figure 1 is a side elevation of a paring knife equipped with the present invention.

Figure 2 is a view looking toward the cutting edge of the knife.

25 Figure 3 is an end view, looking toward the point of the knife.

Figure 4 is a perspective view of the attachment removed from the blade of the knife.

30 Figure 5 is a plan view of one end of the member 11 showing the normal position of the flexible arm in full lines and its operative position in dotted lines.

Referring particularly to the accompanying drawing, and especially to Figure 4, there is shown a perspective view of the device removed from the knife, and wherein it will be seen that it comprises a stationary, or knife blade attaching part 10, and the adjustable gauge part 11.

The part 10 is formed from a single length of wire of suitable gauge, and includes the body portion or bar 12, the opposite ends of which are bent downwardly and laterally, from the same side of said body, as shown at 13 and 14, and then upwardly, to form the yokes 15 and 16. The portion of the yoke 16, outwardly from the body being extended in parallel relation to and in the same 45 plane as the adjacent portion of the end of

the body to form a seat, as shown at 17, from whence the wire extends upwardly and thence downwardly, to form the loop 18, and thence laterally and upwardly, as at 19, to form the loop 20, which receives a portion 55 of the cutting edge of the blade 21, of the knife 22, shown in the other views of the drawing. The other end of the body 12 beyond the yoke 15, is treated in the same manner, as just described, to form the portions 18', 19', and 20'.

The part 11 is formed from a single length of wire, of the same gauge as that of the part 10, and includes the body or bar portion 23, which is arranged in parallel relation to the body 12, of the part 10, and has its opposite ends bent to form the loops 24 and 25, which lie in the same plane, but which extend obliquely from opposite sides of the body ends. The outer leg 28 of the loop 25 extends to a greater extent than the corresponding leg 27, of the loop 24, and is terminally formed with a hook member 29. The outer leg 27, of the loop 24, is slidably disposed through the yoke 15, while its inner leg is disposed outwardly of said yoke 15, and beneath the adjacent end of the body 12. The outer leg 28, of the loop 25 is slidably disposed through the yoke 16, while the other leg portion of said loop is slidably engaged 60 with the under face of the seat.

70 It is to be understood that the longer leg 28, of the loop 25, has a tendency to spring away from the shorter leg of the loop, whereby to engage with one leg of the yoke 16, and thereby move the bar 23 longitudinally of the knife, and urge the leg 27 of the loop 24 against a leg of the yoke 15. Thus, when the ends of the member 11 are properly engaged within the yokes 15 and 16 of the member 10, the legs 27 and 28 will have frictional engagement with the before-mentioned legs of the yokes 15 and 16, so that said member 11 will remain in the different adjusted positions into which it may be pushed or pulled by the operator, whereby to hold the body 23, of the member 11, in proper parallel relation to the cutting edge of the blade, so that said blade may be made to cut slices from fruits 75 80 85 90 95 100

or vegetables, in accordance with the desires of the user.

The gauge device is applied to the knife by wedging the cutting edge of the blade of the knife into the spaces between the inner and outer portions of the loops 20 and 20', which disposes the body portions 12 and 23, of the members 10 and 11 in parallel relation with, and in close proximity to the cutting edge of the knife blade 21.

When the device is thus applied to the knife blade, it will be noted that the leg 28, of the loop 25 will project beneath the thumb of the hand which holds the handle of the knife, and that by applying a slight pressure on the hooked end of said leg, the same may be flexed and released from frictional contact with the side of the yoke 16, and then upon moving the thumb toward or away from the blade, the member 11 will be moved so as to dispose its body or bar 23 close to, or far away from the knife edge, so that the thickness of the paring or slicing of the fruit or vegetable, upon which the knife is operating, passing between the body 23 and the knife edge, will be properly gauged. After having cut slices of the desired thickness, the operator may then cut the slices crosswise, whereby to produce dices.

Attention is called to the fact that the device is adapted to be applied to the blade of a paring knife, without the necessity of any modifications to the knife blade. Furthermore, the adjustment of the device, for the purpose of gauging the thickness of a slice or paring, cut by the blade, is easily, quickly, and safely accomplished by the operator.

What is claimed is:

1. A gauge for a knife comprising a stationary bar having means at its ends for attachment to the blade of a knife, and a gauge bar arranged in spaced parallel relation to said blade attaching bar and movable toward and away therefrom, obliquely extending parallel flexible means on the ends of said bar frictionally and slidably engaged with the end portions of the blade attached bar, one of said obliquely extending means being flexible out of engagement with an end of the blade attached bar to permit movement of the gauge bar toward and away from and in constant parallelism with the stationary bar.

2. A gauge for a knife comprising a bar having terminal means for attachment to the ends of a knife blade, and yoke members between the attaching means and the ends of the bar, one of said attaching means having a seat, and a gauge bar disposed in parallel relation with the first bar for movement toward and away therefrom and having oppositely extending terminal loops each having a leg slidably engaged through a yoke, the yoke engaged leg of one of said loops being adapted for flexing movement into and

out of frictional engagement with the adjacent yoke, and the other leg of said loop being slidable on said seat.

3. A gauge for a knife comprising a bar having terminal yokes each having a knife blade attaching means, and a gauge bar disposed for movement toward and away from the first bar in constant parallel relation therewith, said gauge bar having terminal oblique and oppositely extending loops each having a leg slidable through a yoke, said leg of one of the loops being in engagement with both sides of the adjacent loop and flexible into and out of frictional engagement with one of said loop sides.

4. A gauge for a knife formed from wire and comprising a knife blade attaching member including a bar having its ends formed with knife blade gripping portions and yokes between said ends and gripping portions, a connecting member between one of said yokes and gripping portion forming a seat, and a gauge including a bar arranged in parallel relation with the first bar and adapted for movement toward and away therefrom in constant parallel relation therewith, the ends of said gauge being extended in opposite oblique relation and in the form of open elongated loops, a leg of each of said loops being slidable through a yoke, the other leg of one of said loops slidably engaging on said seat, and the yoke engaging leg of said last-mentioned loop being flexible into and out of frictional engagement with one side of the adjacent yoke.

In testimony whereof, I affix my signature.

ANDREW C. BOLTON.
